UNITED STATES PATENT OFFICE.

CHARLTON E. YOCOM, OF NEW YORK, N. Y., ASSIGNOR OF ONE-HALF TO
JAMES G. MCFADYEAN, OF PITTSBURG, PENNSYLVANIA.

TELEPHONE-TRANSMITTER.

SPECIFICATION forming part of Letters Patent No. 673,350, dated April 30, 1901.

Application filed February 4, 1901. Serial No. 45,921. (No model.)

To all whom it may concern:

Be it known that I, CHARLTON E. YOCOM, a citizen of the United States, residing at New York, in the county of New York and State of New York, have invented certain new and useful Improvements in Telephone-Transmitters; and I do hereby declare the following to be a full, clear, and exact description of the invention, such as will enable others skilled in the art to which it appertains to make and use the same.

This invention relates to telephone-transmitters of that class of instruments in which the to-and-fro motions of the transmitting-diaphragm are caused to vary the resistance of a button, of carbon, placed in the local circuit, and more particularly to transmitters in which the sound-waves are simultaneously directed against the exposed surfaces of two diaphragms.

The objects of the invention are to produce a transmitter of this character which shall be adapted to attain more satisfactory results than are ordinarily obtained in the transmission and reproduction of articulate speech, especially at long distances, and to make a simple and inexpensive instrument the parts of which may be easily assembled and adjusted in position for use or taken apart when desired.

The invention will first be hereinafter more particularly described with reference to the accompanying drawings, which are to be taken as a part of this specification, and then indicated in the claims at the end of the description.

In the drawings, which illustrate only one form of embodiment of my invention, Figure 1 represents a sectional side elevation of a telephone-transmitter constructed in accordance with my invention. Fig. 2 represents a horizontal section on the line 2-2 of Fig. 1, and Figs. 3, 4, and 5 are details of parts of the transmitter in perspective.

The letter A in the drawings may denote a casing or housing in which the transmitting device proper or resistance-varying mechanism and co-operative parts are inclosed, so as to provide a passage-way at each side of the transmitting device communicating with a mouthpiece A', common to both passages and

secured to said casing in any desired manner. Said transmitting device in the form shown is indicated by the letter B and consists of two outer diaphragms B' B' and an intermediate diaphragm C, separated by insulating supports or annuli D D, each of the outer diaphragms having secured thereto or associated therewith a carbon element b, which may be in the form of an ordinary carbon button, and a surrounding electrode-retainer b', which is preferably composed of textile fabric extending from the inner face of the outer diaphragm and having frayed edges, which bear slightly upon the opposing surface of the intermediate diaphragm, the textile material of which said retainer is composed being dense enough to prevent the powdered carbon or other granular material of the electrode confined therein from being displaced by creeping between the fibers thereof and at the same time sufficiently elastic or yielding to permit the diaphragms to vibrate freely for exerting pressure upon the electrode or resistance-varying medium. Within the circular space between the carbon element or button b and the intermediate diaphragm C is placed any suitable comminuted or granular material, such as powdered carbon or carbon-dust. The intermediate diaphragm C is preferably composed of sheet-carbon and is designed to be connected with one pole of the battery or the primary wire of an induction-coil of the usual local circuit, the other side of the circuit being electrically connected with both of the outer diaphragms B' B', as indicated in Fig. 2 of the drawings, in which the circuit may be traced by the wire c, having the branches c', to the two diaphragms B' B', thence through the carbon elements or buttons b and the granular electrodes to the carbon or intermediate diaphragm C, and thence to the wire c², completing the circuit through the instrument. For conveniently holding together the diaphragms, insulating rings, and interposed electrodes and retaining means, assembled as above indicated and shown in the drawings, a resilient or other suitable band E, having side flanges e, may be slipped over the assembled parts, with said flanges overlapping the marginal portions of the outer diaphragms, and may be retained

thereon so as to confine said parts in fixed positions relatively to each other by the resiliency of the said band, causing it to close upon the assembled parts, or by securing the ends thereof together, as may be found most desirable in practice. Such retaining-band may be dispensed with, however, and the several diaphragms and co-operative parts forming the transmitter proper may be secured together in any desired manner. By the described construction I produce a transmitting device in which the sound-waves are adapted to act simultaneously upon the exposed surfaces of the two outer diaphragms, between which and the inner diaphragm there is an unoccupied space at each side of the latter surrounding each electrode, and the amount of electrode-surface is doubled as compared with transmitters of the usual construction, in which a granular electrode is employed between two diaphragms, one in electrical connection with one side and the other with the other side of the circuit, and I thus secure a highly sensitive and efficient instrument, which is especially adapted for transmitting messages to long distances as well as desirable for local use. Moreover, when in a state of rest the resistance in the electric circuit is comparatively very high, which tends to prolong the life of the battery in the local circuit.

This transmitting device may be inclosed in any suitable case or housing having passage-ways for dividing the sound-waves in such manner as to cause the same to act simultaneously against the exposed faces of both outer diaphragms. A convenient form is illustrated in the drawings, in which a simple band a is passed around the transmitting device and provided with lugs a' on the interior thereof to prevent lateral movement of said device, the said band having sufficient width to leave a space or passage-way a^2 at each side of the transmitter in communication with a mouthpiece A' , common to both passages. Said mouthpiece may have a screw-threaded portion to be screwed into a coupling-piece a^3 , fitting around an opening in the retaining-band a , and the open ends of the latter may be closed by side pieces a^4 , having annular flanges a^5 thereon, which extend into the drum or cylinder formed by the retaining-band and are secured thereto by suitable bolts and nuts or other fastenings.

Having thus fully described my invention, what I claim as new, and desire to secure by Letters Patent of the United States, is—

1. A multiple-diaphragm telephone-transmitter, comprising three diaphragms slightly separated each from the other by insulating supports or annuli; the two outer diaphragms each having a carbon element about its center, a granular electrode interposed between each of said carbon elements and said intermediate diaphragm, and electrical connections for completing the usual local circuit through the instrument by connecting both

outer diaphragms with one side and the intermediate diaphragm with the other side of the circuit, substantially as described. 70

2. A multiple-diaphragm telephone-transmitter, comprising two outer diaphragms and an intermediate diaphragm separated each from the other by an insulating support or annulus interposed between the intermediate 75 and each outer diaphragm, each of the latter having a centrally-disposed carbon element, a granular electrode interposed between each of said carbon elements and said intermediate diaphragm, means for securing said parts together, and electrical connections for completing an electric circuit through the instrument, substantially as described.

3. A multiple-diaphragm telephone-transmitter, comprising two outer diaphragms each 85 having a carbon element at its center, an intermediate diaphragm composed wholly or in part of sheet-carbon, an insulating support or annulus at each side of said carbon diaphragm separating it from the outer diaphragms, and a granular electrode interposed between each of said carbon elements and said intermediate diaphragm, together with means for holding said parts together.

4. A multiple-diaphragm telephone-transmitter, comprising two outer diaphragms each having a carbon element at its center, an intermediate diaphragm composed wholly or in part of sheet-carbon, an insulating support or annulus at each side of said carbon diaphragm separating it from the outer diaphragms, and a granular electrode interposed between each of said carbon elements and said intermediate diaphragm, together with means for holding said parts together, and means for electrically connecting both outer diaphragms with one side and the intermediate diaphragm with the other side of the usual local circuit. 95

5. A multiple-diaphragm telephone-transmitter, comprising two outer diaphragms each having associated therewith a centrally-disposed carbon element, an intermediate diaphragm composed wholly or in part of sheet-carbon, an insulating support or annulus interposed between each outer diaphragm and the intermediate diaphragm, a granular electrode at each side of said intermediate diaphragm in contact with one of said centrally-disposed carbon elements, and textile material projecting from the outer diaphragms and surrounding the electrode for retaining the same about the center of the intermediate diaphragm. 110 115

6. In a multiple - diaphragm telephone-transmitter, two outer diaphragms, each carrying a centrally-disposed carbon element, an intermediate diaphragm, an insulating-annulus separating each outer diaphragm from said intermediate diaphragm, a granular electrode interposed between each of said carbon elements and said intermediate diaphragm, and means for holding said parts together, in combination with a casing inclosing said as- 125 130

sembled parts and provided with a passage-way for sound-waves at each side thereof, and a mouthpiece communicating with said passage-ways.

5 7. In a multiple-diaphragm telephone-transmitter, the combination of outer diaphragms each having a carbon element associated therewith, an inner diaphragm, insulating-supports separating the inner and outer diaphragms, a granular electrode interposed between said carbon elements and said intermediate diaphragm, and a retainer composed of textile material surrounding the granular electrode and confining the same in place 15 about the center of the inner diaphragm.

8. A multiple-diaphragm telephone-transmitter, comprising several diaphragms each having a carbon element associated therewith, an insulating-support separating the outer and inner diaphragms, a granular electrode interposed between the carbon elements on the opposing surfaces of all the diaphragms, and non-conducting flexible material surrounding the electrodes and confining the same about the centers of the diaphragms.

9. A multiple-diaphragm telephone-transmitter, comprising several diaphragms each having a carbon element associated therewith, an insulating-support separating the outer and inner diaphragms, a granular electrode interposed between the carbon elements on the opposing surfaces of all the diaphragms, and non-conducting flexible material surrounding the electrodes and confining the same about the centers of the diaphragms, in combination with an inclosing case having side passages and a mouthpiece common to both passages, substantially as described.

10. A multiple-diaphragm transmitter comprising two outer diaphragms each having a centrally-disposed carbon element associated therewith, an intermediate carbon diaphragm, an insulating and separating annulus arranged between each of said outer diaphragms and said carbon diaphragm, textile material extending inward from said outer diaphragms in the form of annuli, and granular electrodes within said annuli in contact with opposing surfaces of said carbon elements and intermediate diaphragm, substantially as described.

11. In a telephone-transmitter, the combination with a diaphragm secured between in-

sulating-annuli surrounding the marginal portions thereof, of a pair of diaphragms secured to the outer sides of said annuli, a carbon element on the inner surface of each of said outer diaphragms, and a ring-like retaining device composed of textile material surrounding the carbon element and having frayed edges in contact with said intermediate diaphragm for retaining a granular electrode confined between the carbon element and intermediate diaphragm, substantially as described.

12. In a telephone-transmitter, the inclosing case having a mouthpiece, in combination with the transmitting device properly arranged within the case so as to provide a passage-way at each side thereof communicating with said mouthpiece, said transmitting device consisting of several diaphragms, the outer ones forming the inner walls of said passages, an intermediate diaphragm and support therefor separating the latter from the outer diaphragms, a centrally-disposed carbon element associated with each of said outer diaphragms, a granular electrode and means for supporting the same between each of said carbon elements and said intermediate diaphragm, and circuit-wires for completing the electric circuit through said electrodes and intermediate diaphragm.

13. The combination in a telephone-transmitter, of a casing having a passage at each side thereof and a mouthpiece communicating therewith, two diaphragms forming the inner walls of said passages each having a carbon element about its center, an intermediate diaphragm, an insulating-support interposed between each of said outer diaphragms and said intermediate diaphragm, a granular electrode interposed between each of said carbon elements and said intermediate diaphragm, and circuit-wires for completing the usual local circuit leading from said carbon diaphragm to one side of the circuit and from both of said outer diaphragms to the other side of the circuit, substantially as described.

In testimony whereof I affix my signature in presence of two witnesses.
